UNITED STATES PATENT OFFICE.

WALTER BURNHAM, OF CHICAGO, ILLINOIS.

RETURN-PIPE FOR STEAM-CIRCUITS.

SPECIFICATION forming part of Letters Patent No. 394,823, dated December 18, 1888.

Application filed February 21, 1888. Serial No. 264,807. (No model.)

To all whom it may concern:

Be it known that I, WALTER BURNHAM, of Chicago, in the county of Cook and State of Illinois, have invented certain new and useful Improvements in Return-Pipes for Steam-Circuits; and I do hereby declare that the following is a full, clear, and exact description thereof, reference being had to the accompanying drawings, and to the letters of reference marked thereon, which form a part of this specification.

This invention relates to improvements in systems of pipe-connections of steam-generators in which it is the purpose to abstract water of condensation and entrainment from a steam-pipe, and to take the water so withdrawn through an adjunctive pipe by a flow of steam in the latter, which steam-flow is forced by an excess of pressure in the steam-pipe over that in the adjunctive pipe at a point remote from its connection with the steam-pipe. Commonly the adjunctive pipe will be employed to lift the water and to return it to the generator, and the system herein illustrated shows this pipe terminating in the generator for that purpose, and the adjunctive pipe will be herein generally called the "return-pipe."

The object of the present invention is to provide for a more perfect control of the water movement in the return-pipe when required.

To this end it consists, first, in the provision of a plurality of return-pipes in connection with a single steam-pipe; secondly, in the insertion of a valve in each of the plural return-pipes near its junction with the steam-pipe; and, thirdly, in the addition of a branch pipe leading from the steam-space of the steam-pipe into a return-pipe beyond the regulating-valve therein, if one be present.

These improvements are in a sense cumulative; but they may be used separately or together, according to the requirements of particular situations.

In the drawing, which presents a diagrammatic view of apparatus containing my improvements in connection with a generator, (shown in transverse section,) A represents a steam-generator, B a steam-pipe leading therefrom, and C a return-pipe leading from the steam-pipe to a point above the wa-

ter-line of the generator, thence downward into the generator, and in this instance terminating in the water-space thereof. These 55 elements mentioned constitute the system of steam-pipe connections described in certain applications for patent filed by William Irving, February 7, 1888, Serial Nos. 263,224 and 263,225.

L represents a separator connected in the steam-pipe B, as also set forth in one of said Irving applications.

B' is a prolongation of the steam-pipe leading to an engine or other steam-using device. 65

As fully described in the said applications of Irving, in a system comprising a generator, a steam-pipe and a return-pipe having a drainage-connection with the generator, the return-pipe operates to return the water of 70 condensation and of entrainment in the steam-pipe to the generator. This is accomplished by condensation in or escape from the return-pipe at a point contiguous to the water standing in the leg thereof, which 75 gives at such point a less pressure than that of the steam-pipe, from which difference in pressure results a forcible flow of steam in the return-pipe from the steam-pipe toward the generator. The steam in its rapid movement from the steam-pipe through the return-pipe carries the water in detached masses with and before it and delivers it into the descending leg of said return-pipe, where it joins the water column therein and ultimately 80 settles into the body of water in the generator.

In the case of a return-pipe connected with a steam-pipe at a point below the water-level in the generator, as shown in the drawing, 90 if water is supplied to or is allowed to accumulate in the lower part of the return-pipe faster than it can be lifted by the steam-flow, or if allowed to accumulate so as to cut off the steam-flow, then the water in the generator 95 will rise through the leg of the return-pipe and flow outwardly from the generator to the steam-pipe, and thus defeat the operation sought to be obtained. To avoid this result provision must be made for a constant steam-flow from the steam-pipe to the low-pressure chamber in the return-pipe. Now the extent to which the pressure in the low-pressure space in the return-pipe may be reduced be-

low that of the steam-pipe is restricted by the available space for the water-leg of the return-pipe, since the height of the water column will depend upon the difference between the 5 pressure in the generator and that in the low-pressure space in the return-pipe above the water column. It follows that in many situations a single return-pipe cannot be made to return (in the necessarily-broken form or in 10 detached masses) all the water which the steam-pipe delivers thereto, and I therefore provide a plurality of return-pipes, each having only such a reduction of pressure in its low-pressure chamber as is allowable by the 15 vertical space for the water-leg, and each able therefore to carry up a portion only of the water to be taken from the steam-pipe, but together able to lift it all. By thus using a plurality of return-pipes, each having a short 20 water column in its descending leg, a large quantity of water may be taken from the steam-pipe in those situations where there is not room for a single return-pipe with the higher water column that would be necessary. 25 To obtain an equable division of water between two or more return-pipes, C, they should be so connected with the steam-pipe B or with the separator L as to take therefrom quantities correctly proportioned to their respective powers. A certain limitation of 30 steam and water supply to each of the pipes C will be insured by providing each of them with a valve, C', close to its receiving end, which valve may regulate the size of the inlet to said pipe. In order to use this inlet for 35 the admission of water only, a separate steam-pipe, D, is shown having an upper open end in the steam-space of the separator and extending to a connection with the pipe C below 40 or beyond the valve C'. Such a pipe will supply steam to the pipe C independently of the water-inlet to said pipe. To control the amount of steam admitted to the pipe C through the pipe D, the latter is shown provided with a valve, D'. 45 Though the return-pipe C is shown as connected with a steam-pipe at a point below the water-level of the generator, it is to be understood that the invention applies as well to 50 those return-pipes which rise from a point at or above the water-level of the generator. Indeed, it also applies to returns which do not rise at all, but in which reduced-pressure chambers are to be established for the purpose of stimulating active circulation with a 55 view to obtaining hotter and dryer steam from the steam-pipe for an engine or other steam-using device, as set forth in one of said applications for patent filed by William Irving.

In other applications for patent filed by me I point out that the pipe C, here called the "return-pipe," may terminate elsewhere than in the water-space of the generator, and even 60 externally to the generator, being provided

with an upturned end or rising portion following a descent and containing a water column in one form or another adapted to hold its place against opposing pressures, while permitting discharge of water at its end remote from the steam-pipe. The present improvements are to be understood as also applying to those and similar cases. It is also to be understood that the water to be carried by the return-pipe may be derived in part 75 from other sources than the steam-pipe.

I claim as my invention—

1. The combination, with a steam-generator and a steam-pipe leading therefrom, of a plurality of return or discharge pipes connected with the steam-pipe, each containing a water column remote from the steam-pipe, and a space adjacent to the water column having steam communication with the steam-pipe and subject to lower pressure than the 85 steam-pipe, substantially as described.

2. The combination, with a steam-generator and a steam-pipe leading therefrom, of a plurality of return or discharge pipes connected with the steam-pipe, each provided 90 with a regulating-valve and each containing a water column remote from the steam-pipe, and a steam-space communicating through the valve with the steam-pipe and subject to lower pressure than the steam-pipe, substantially as described.

3. The combination, with a steam-generator and a steam-pipe leading therefrom, of a discharge or return pipe having drainage-connection with the steam-pipe, and a pipe leading 100 from the steam-space of the steam-pipe into said discharge or return pipe, substantially as described.

4. The combination, with a steam-generator and a steam-pipe leading therefrom, of a 105 discharge or return pipe having a drainage-connection with the steam-pipe and provided with a valve, and a pipe leading from the steam-space of the steam-pipe into the discharge-pipe beyond the valve in the latter.

5. The combination, with a steam-generator and a steam-pipe leading therefrom, of a discharge-pipe having drainage-connection with the steam-pipe and provided with a valve, and a valved pipe leading from the 115 steam-space of the steam-pipe into the discharge-pipe beyond the valve therein.

6. The combination, with a steam-pipe leading from a generator, of a separator, a discharge-pipe leading from the water-space of 120 the separator, and a pipe leading from the steam-space of the separator into the discharge-pipe.

In testimony that I claim the foregoing as my invention I affix my signature in presence 125 of two witnesses.

WALTER BURNHAM.
